C. E. P. GREIFF & C. F. SCHREIBER.
AUTOMOBILE SAFETY LOCK.
APPLICATION FILED DEC. 22, 1914.

1,192,516.

Patented July 25, 1916.

UNITED STATES PATENT OFFICE.

CHRISTIAN E. P. GREIFF AND CHARLES F. SCHREIBER, OF CHICAGO, ILLINOIS, ASSIGNORS OF ONE-THIRD TO CARL J. KLEIN, OF CHICAGO, ILLINOIS.

AUTOMOBILE SAFETY-LOCK.

1,192,516.

Specification of Letters Patent. Patented July 25, 1916.

Application filed December 22, 1914. Serial No. 878,529.

To all whom it may concern:

Be it known that we, CHRISTIAN E. P. GREIFF and CHARLES F. SCHREIBER, former subjects of the Emperor of Germany, who have declared our intention of becoming citizens of the United States, and residents of the city of Chicago, county of Cook, and State of Illinois, have invented certain new and useful Improvements in Automobile Safety-Locks, of which the following is a specification.

Our invention relates to improvements in automobile safety locks, and has for its object the provision of an improved construction of this character for preventing unauthorized removal of an automobile.

The invention consists in the combinations and arrangements of parts hereinafter described and claimed.

20 The invention will be best understood by reference to the accompanying drawing forming a part of this specification, and in which,

Figure 1 is a sectional view illustrating 25 a lock embodying our invention, Fig. 2, a section taken at right angles to Fig. 1, Fig. 3, a section taken on line 3-3 of Fig. 2, and Fig. 4, a detail view showing a cam member employed in the construction in a 30 different position from that illustrated in Fig. 2.

The preferred form of construction as illustrated in the drawing comprises an ordinary gasolene tank 5 mounted in the car 35 in the usual manner, and provided with a discharge pipe 6 leading from the bottom thereof. Discharge pipe 6 connects with a valve casing 7 arranged within a protecting casing 8 located around the same. Valve 40 casing 7 is provided with a discharge pipe 9 leading to the engine of the automobile, and a reciprocatory plug valve 10, as indicated. Valve 10 is provided with a valve stem 11 having a slot and pin connection 12 with an 45 arm 13 provided with an eccentric strap 14 engaging an eccentric 15 on an operating shaft 16, a compression spring 11' being interposed between the lower end of arm 13 and a collar 12' on valve stem 11. By this 50 arrangement, it will be observed, that valve 10 may be opened or closed by turning shaft 16 in either direction and that a yielding connection is afforded between the eccentric

15 and the valve 10 holding said valve to its seat.

55 Shaft 16 is provided with a locking cam 17 having a lug 18 at one side provided with two abrupt sides and a shoulder 19 on the other side having one side abrupt and the other side constituting a cam surface 19'. 60 Cam member 17 cooperates with a spring bolt 20 of an ordinary combination lock 21, said bolt being provided with a notch 22 adapted to receive lug 18 and engage with shoulder 19, as indicated. The lock 21 is 65 provided with the usual operating knob 23 and shaft 16 is provided with an operating handle 24, as shown.

By this arrangement, it will be observed, 70 that when valve 10 is closed, lug 18 engages notch 22 in bolt 20 so that if the combination of lock 21 is thrown the supply of gasolene is cut off from the engine and can only be renewed by one knowing the combination of lock 21. To open the valve, the 75 combination of lock 21 is set and bolt 20 withdrawn, whereupon shaft 16 may be rotated through substantially one hundred and eighty degrees, and shoulder 19 engaged with notch 22, as indicated in Fig. 4, thus 80 holding the valve open. When it is desired to close the valve, all that is necessary is to rotate shaft 16 counter-clock-hand-wise, when cam surface 19' will automatically disengage shoulder 19 from notch 22 and lug 18 85 will automatically engage with said notch to lock the valve in closed position when the combination is thrown.

While we have illustrated and described 90 the preferred form of construction for carrying our invention into effect, this is capable of variation and modification without departing from the spirit of the invention. We, therefore, do not wish to be limited to 95 the precise details of construction set forth, but desire to avail ourselves of such variations and modifications as come within the scope of the appended claim.

Having described our invention what we claim as new and desire to secure by Letters 100 Patent is:

The combination of a valve; an operating shaft; an operative connection between said shaft and valve; a lock provided with a spring bolt having a notch in its end; and 105 a cam member on said shaft provided at one

2

side with a projection having abrupt shoulders on each side thereof and adapted to engage and interlock with said notch and at its other side with a projection having an abrupt shoulder at one side adapted to engage and interlock with said notch and a cam surface at the other side adapted to force back said bolt upon rotation of said shaft in one direction, the arrangement being such that said first mentioned projection engages said notch when said valve is closed

and said second mentioned projection engages said notch when said valve is open, substantially as described.

In testimony whereof we have signed our 15 names to this specification in the presence of two subscribing witnesses.

CHRISTIAN E. P. GREIFF.
CHARLES F. SCHREIBER.
